GAME APPARATUS

Bruno Radtke, Chicago, Ill., assignor to Exhibit Supply Company, Chicago, Ill., a corporation of Illinois

Application March 30, 1936, Serial No. 71,607

11 Claims. (Cl. 273—138)

This invention relates to game apparatus.

It is an object of this invention to provide an improved game apparatus which is relatively simple and inexpensive in construction and efficient in use.

Another object of the present invention is to provide certain novel improvements in an amusement apparatus of the type in which a plurality of balls are adapted to run down a vertically arranged series of ball runways or baffles which are arranged in the cabinet of the apparatus, upon the front of the same, the said balls changing their relative position as they travel down the said runways.

Another object of the present invention is to provide an amusement apparatus which is played with a plurality of balls and includes a score-indicating instrumentality, and means including a device actuated by one of said balls for operating said score-indicating instrumentality, said means being actuated by the said one of said balls only if and when the said one of said balls is of a predetermined size or diameter.

An additional object of the invention is to construct the same in such a manner that the said means is effective to operate said score-indicating instrumentality only if and when the aforesaid one of said balls is larger in size and diameter than the others of said balls.

Another object of the present invention is to provide an amusement apparatus of the type which includes a cabinet having embodied therein vertically extending series of ball runways, a group of balls adapted to travel down the said runways and to change their relative positions as they travel, said apparatus including a ball seat arranged at the bottom of said runways and adapted to receive balls from the latter, a score-indicating instrumentality, and means including a device actuated by the said balls when the same are disposed upon said ball seat for operating said score-indicating instrumentality, said device being actuated only when the said balls are arranged upon said ball seat in a predetermined sequence.

An additional object of the present invention, ancillary to the foregoing objects, is to construct the device in such a manner that the said device is actuated only if and when the larger one of said balls is the first ball to enter onto said ball seat, that is, when the larger one of said balls is the "winning" ball, that is, is the first ball to enter onto said ball seat.

Other objects will appear hereinafter.

The invention consists in the novel combina-

tion and arrangement of parts to be hereinafter described and claimed.

The invention will be best understood by reference to the accompanying drawings showing the preferred form of construction, and in which:

Fig. 1 is a vertical sectional view through the cabinet of the new amusement apparatus, partly in elevation, and showing a preferred embodiment of the same;

Fig. 2 is a vertical sectional view on line 2—2 in Fig. 1;

Fig. 3 is a sectional view, on line 3—3 in Fig. 2, showing the ball seat;

Fig. 4 is a top plan view of the ball seat shown in Fig. 3;

Fig. 5 is a fragmentary elevational view of the switch-operating mechanism embodied in the device;

Fig. 6 is a diagrammatic view of an electrical circuit embodied in the device;

Fig. 7 is a sectional detail view on line 7—7 in Fig. 5;

Fig. 8 is a sectional detail view on line 8—8 in Fig. 5; and

Fig. 9 is a perspective view of a game apparatus embodying the present invention.

A preferred form of the new amusement apparatus is shown in the drawings, is therein generally indicated at 10, and comprises a cabinet 11, which is of the so-called upright type, and which includes a vertically extending transparent front wall 12. Arranged in the cabinet 11, behind the transparent front wall 12, is a vertically extending wall 13 on which is arranged a vertically extending series of ball runways or baffles 14, and arranged above the baffles 14 are two runways 15 and 16 by means of which balls are directed onto the baffles 14 from an opening 17 which is formed in a vertically extending wall 18 of the cabinet, the balls being elevated from the bottom of the cabinet up to the opening 17 and are dumped out onto the runway 15, by means of an elevating device, generally indicated at 19, the arrangement of the baffles 14 and runways 15—16 forming the subject matter of Design Patent No. 87,840, granted to Claude R. Kirk on September 27, 1932.

Arranged adjacent the bottom of the cabinet 11, and in communication with the lowermost one of the runways or baffles 14, so as to receive balls from the latter, is a ball seat 20 (Figs. 2, 3 and 4) onto which balls are adapted to run from the lowermost of the baffles or runways 14.

Slidably mounted in the cabinet 11, on a guide 110 (Fig. 1) and at one side of the ball seat 20,

55

is a gate 94. The ball seat 20 has an inclined bottom surface 95 by which balls arranged upon the seat 20 are inclined or directed against the gate 94. Provided on the gate 94 (Fig. 1) is an arm 111 and engageable with this arm 111 is a flange or extension 96 which is formed on the ball-conveyor or carrier 97 by which the balls are conveyed from the ball seat 20 up to the opening 17 through which they are dumped onto the uppermost runway 15, it being understood in this connection that the ball elevating device does not form a part of the present invention. This ball carrier or bracket 97 is slidably mounted on an inclined vertically extending trackway 98 which is arranged in the cabinet 11 (Fig. 2) and this ball carrier 97 is operated by a chain 99 to which is attached a handle 100 which has a portion disposed exteriorly of the cabinet 11.

The present amusement apparatus is adapted to be played with a plurality of balls 21 and 22 (Fig. 3) and it will be noted by references to this figure that the ball 21 is somewhat larger in size or diameter than the balls 22. The reason for thus having the ball 21 slightly larger in size or diameter than the balls 22 will be explained hereinafter.

Provided in the ball seat 20 are two spaced openings 23 and 24 (Fig. 3), and mounted on the ball seat 20, on the bottom side thereof is a switch 78. This switch 78 includes a contact 25 which has an angled end portion 26 and this end portion 26 projects upwardly through the opening 23 in the ball seat 20. Likewise mounted on the ball seat 20, on the bottom side thereof, and engageable with the contact 25, is a contact 27 which also forms part of the switch 78. The contact arm 25 also has an angled end portion 29 which projects upwardly through the opening 24 in the ball seat 20. Likewise mounted on the ball seat 20 and forming part of the switch 78 is a contact 30 and this contact 30 is engageable with the contact 25.

Arranged in the cabinet 11 is a horizontally extending shaft 31 (Fig. 3) and mounted, that is, fixed on this shaft 31 is an arm 32. This arm 32 has an end portion 33 which is engageable with the relatively large ball 21 (Fig. 3) when the latter is in "winning" position, that is, when the ball 21 is the first of the group of balls to enter onto the ball seat 20.

Also mounted on the shaft 31 (Fig. 2), at the opposite end of the same from the arm 32, is an upwardly extending arm 34, which is normally urged (in a clockwise direction, Fig. 1) by a spring 112, and this arm 34 has a lateral extension 35 which is engageable with an arm 36 which is carried by a horizontally extending shaft 37.

Mounted, that is, fixed on the shaft 37 is an arm 38 and this arm 38 is pivotally connected, as at 39, to an arm 40, the arm 38 having a latched extension 101 which is engageable with the arm 40 (Fig. 5). This arm 40 has a laterally projecting lug or portion 41 and this lug 41 is engageable with a contact 42 which is attached, as at 43, to a stationary support 44, this contact 42 forming part of a switch 79. Likewise attached, as at 43, to the support 44, and forming part of the switch 79, is a contact 45 which is engageable with the contact 42. Also attached as at 43, to the support 44 is a contact 46, which forms part of the switch 79, and this contact 46 is normally held in the position in which it is shown in Fig. 5 by means of a lug 47 which is carried by the arm 48 of the support 44.

Mounted in the cabinet 11 is an electromagnet

49 (Fig. 5) and attractable by this electromagnet 49 is a latch member 50 which is pivotally mounted in the cabinet, as at 52. Attached to this latch member 50 is a spring 53 which normally urges the latch member 50 (counterclockwise, Fig. 5) into engagement with a stop 103, so as to move one end portion 54 of the latch member 50 into engagement with an arm 55 of a member 56 which is pivotally mounted in the cabinet 11, as at 51 (Fig. 5), this member 56 being urged (in a clockwise direction, Fig. 5) by means of a spring 57. Formed on this member 56 is an arm 59 (Fig. 5) which bears against the lug 41 when the member 56 is latched, by the parts 54—55, in the position in which they are shown in Fig. 5.

The member 56 also includes a bifurcated arm 60 and projecting between the fingers 61 and 62 of the bifurcated arm 60 is a lug 63 which is attached to the piston 64 of a dash pot or timing device 65.

Slidably mounted in the side wall 66 of the cabinet 11 is a coin slide 67. This coin slide 67 has an upward extension 68 at its inner end, this extension 68 having a pin and slot connection 69 with a link 70. This link 70 is pivotally connected, as at 71, to an arm 72 of a bell crank lever 73 which is pivotally mounted in the cabinet 11, as at 74, this bell crank 73 being supported by means of a supporting bracket 75. This bell crank lever 73 has an arm 76 which is engageable with an arm 77 of the member 56 (Fig. 2), for a reason to be explained hereinafter.

The inner end portion 80 of the coin slide 67 is engageable with the upper end portion 81 of a lever 82 which is pivotally mounted, between its ends, as at 83, in the cabinet 11 (Fig. 2). This lever 82 has a lower end portion 84 and this lower end portion 84 has an angled extension 85. This extension 85 of the arm 84 is engageable under an arm 86 of the gate 94 so as to hold the latter in raised position. To this end the extension 85 of the arm 84 is urged into a position under the arm 86 of the gate 94 (as in full lines, Fig. 1) by means of a spring 87. This spring 87 is attached at one end to the lower end portion of the arm 84 of the member 82 and at its other end this spring 87 is attached to a member 104 which is pivotally mounted in the cabinet 11, as at 107, (Fig. 1). This member 104 has an arm 108 which is engageable under the bottom edge of the ball carrier 97, (Fig. 1).

The switch 78, the contacts 45 and 42 of the switch 79, and the electromagnet 49, are arranged in an electrical circuit 88 (Fig. 6) and this circuit 88 also includes a source of energy 89, which may be a battery of dry cells or the like arranged in the cabinet 11.

Associated with the circuit 88 is a second circuit 102 and this circuit 102 includes the current source 89, the switch 78, the contacts 42 and 46 of the switch 79, and a score-indicating instrumentality 90 which has the form of a light bulb 90 although other instrumentalities may be used in place of the light bulb 90. The score-indicating instrumentality or light bulb 90 is arranged in the cabinet 11 behind a slight opening 91 so as to be visible from outside the cabinet 11 when illuminated.

Operation

Balls are elevated in the cabinet 11 (by means of the elevating device 19) up to the level of the

opening 17 and they are dumped from the carrier 97 through the opening 17 onto the upper runway 15, whence they will run down the latter onto the runway 16 and thence onto the runway 5 ways or baffles 14. As the balls run down the baffles 14 their positions relative to each other are changed, and eventually the balls come to rest on the ball seat 20, as shown in Fig. 3. When the balls come to rest on the ball seat 20 in the sequence in which they are shown in Fig. 3, one of the smaller balls 22 will be disposed in engagement with the end portion 26 of the contact member 25 and the relatively large ball 21 will be disposed in engagement with the end portion 29 of the contact member 25, thus closing the switch 78 and thereby closing the circuit 88 to the electromagnet 49, whereupon current will flow as follows: From one side of the current source 89, by way of the conductor 90, through the switch 78, thence by way of the conductor 91, through the contacts 42 and 45, of the switch 79 (Fig. 6), thence by way of the conductor 92, into the electromagnet 49, through the latter, and thence by way of the conductor 93 back to the other side of the current source 89, thereby energizing the electromagnet 49.

When the electromagnet 49 is thus energized it will attract its pivotal armature, that is, the latch member 50, (clockwise, from full to dotted line position, Fig. 5), thereby moving the end portion 54 of the latch member 50, against the action of the resetting spring 53, out of latching engagement with the arm 55 of the member 56, whereupon the spring 57 will urge the member 56 (clockwise, Fig. 5). During this movement of the member 56 (clockwise, Fig. 5) the arm 59 thereof will move away from the lug 41 on the arm 40 (clockwise, Fig. 5), and the lug 41 will be moved away from the contact 42, by the action of the spring 112 on the parts 31—34—35—36—37—38—101—40, in a manner which will be described more fully hereinafter, whereupon the contact 42, acting under the force of its own resiliency, will move out of engagement 45 with the contact 45 and thus open the circuit 88 to the electromagnet 49, thereby deenergizing the latter. During this operation the contact 42 moves, by the action of its own resiliency, into engagement with the contact 46, thereby closing 50 the circuit 102 to the score-indicating instrumentality or light 90, whereupon current will flow as follows: From one side of the current source 89 by way of the conductor 90, through the switch 78, thence by way of the conductor 91 to the contacts 42 and 46 of the switch 79, thence through the score-indicating instrumentality 90, and thence by way of the conductor 109 back to the current source 89, thereby energizing the score-indicating instrumentality 90, 60 and thus illuminating the lamp 90 so as to indicate that the player has been successful in playing the game, that is, to indicate that the relatively large ball 21 has been the first ball (of the group of balls shown in Fig. 3) to run down the baffles or runways 14 and enter onto the ball seat 20, it being understood, in this connection, that any desired or suitable score-indicating instrumentality may be employed, in place of the lamp 90, which is shown merely for the purpose of illustrating the invention and is not to be construed as a limitation of the kind of score-indicating instrumentality which may be used in the same.

When the arm 59 of the member 56 is moved 70 away from the lug 41 on the member 40 (clock-

wise, Fig. 5), by the action of the spring 57, the spring 112 rocks the shaft 31 and the arms 34 and 32 carried thereby (clockwise, Fig. 1), thereby moving the lateral extension 35 of the arm 34 into engagement with the arm 36 and thereby rocking the latter and the shaft 37 and the arm 38 which is carried by the shaft 37 (counterclockwise, Fig. 1). During this movement of the arm 38 the angled extension 101 thereof engages the arm 40 (Fig. 5) and thereby pivots the member 40, (in a 10 counterclockwise direction, Fig. 5), with the arm 38, thereby moving the lug 41 on the member 40 away from the contact 42 and thus permitting the latter to move, under the action of its own resiliency, (counterclockwise, Fig. 5).

It will be noted that when the spring 112 acts upon the shaft 31 to rock the same (clockwise, Fig. 1) the arm 32 which is mounted on the shaft 31, is pivoted in the direction of the ball which is disposed upon the ball seat 20 in engagement with the end portion 29 of the contact 25 (Fig. 3) and it will also be noted, in this connection, that the extent of the movement of the members 38 and 40, and of the lug 41 on the member 40 (counterclockwise, Fig. 5), (by the action of the spring 112, shaft 31, arm 34—35, arm 36, and shaft 37) is limited by the engagement of the arm 32—33 with the particular ball which is disposed upon the ball seat 20 in engagement with the contact 29, this particular ball being the "winning" ball, 30 that is, the ball which is the first of the group of the same to enter onto the ball seat 20. It will therefore be seen that when the winning ball which is disposed on the ball seat 20, in engagement with the contact 29, is the relatively large 35 ball 21, the extent of the movement which is permitted the arm 32, shaft 31 and also the parts 36—37—38—101—40 and 41 will be relatively less than if the said "winning ball" is one of the smaller balls 22. Hence it will be seen that if the winning ball is the larger ball 21 the member 40 and the lug 41 thereon will be moved, (by the parts 112—31—34—35—36—37—38—101—40) only far enough (counterclockwise, into position "A", Fig. 5) to allow the contact 42 to move, 40 by its own resiliency, out of engagement with the contact 45 (so as to open the circuit 88 to the electromagnet 49) and into engagement with the contact 46, so as to close the circuit 102 to the score-indicating instrumentality or light 90. 50

However, if the "winning" ball is one of the smaller balls 22, (rather than the large ball 21) then the extent of movement which will be permitted the shaft 31, arm 32, and associated parts 34—35—36—37—38—101—40 and 41, under the 55 action of the spring 112, will be greater than when the winning ball is the large ball 21 and, in this event, the lug 41 on the member 40 will move (counterclockwise, into position "B", Fig. 5) into engagement with the contact 46 and will thus move the contact 46 out of engagement with the contact 42, thereby opening the circuit 102 (Fig. 6) to the score-indicating instrumentality or lamp 90, and hence the latter will not be actuated or energized when the winning ball is one of the 60 smaller balls 22 rather than the large ball 21.

It is possible in this connection, that the foregoing arrangement of parts could be reversed so that the lug 41 on the member 40 would move into engagement with the contact 46 so as to 70 open the circuit 102 to the score-indicating instrumentality when a relatively small ball, rather than a relatively large ball, is the winning ball disposed upon the ball seat 20 in engagement with the contact 29. In this event, of course, it would 75

be necessary to have one of the balls in the group smaller in diameter than the other rather than larger, as in the preferred embodiment of the invention shown.

5 In order to reset the parts back into their initial position (as in full lines, Fig. 5), a proper coin is inserted into the coin slide 67 and the latter is pushed in (right to left, Fig. 1) and this movement of the coin slide 67 acts, through the 10 link 70, to pivot the bell crank 73 (clockwise, from full to dotted line position, Fig. 1), thereby moving the arm 76 of the bell crank 73 into engagement with the arm 77 of the member 56, and thus pivoting the latter (counterclockwise, from dotted 15 to full line position, Fig. 5), against the action of the spring 57. During this operation the arm 55 of the member 56 rides over the latch member or armature 50 of the electromagnet 49 and when the arm 55 of the member 56 reaches the outer 20 end of the latch arm 50 the spring 53 acts upon the latch member 50—51 to urge the end portion 54 thereof into latching engagement with the arm 55 of the member 56 (as in full lines, Fig. 5).

It is to be noted that when the member 56 is 25 moved (clockwise, Fig. 5) by the spring 57, so as to move the arm 59 thereof out of engagement with the lug 41 and thus allow the latter, in turn, to move away from the contact 42, the arm 61 of the member 56 engages the lug 63 on the piston 30 64 of the dash pot 65 and thereby moves the latter (upwardly, from full to dotted line position, Fig. 5) and, when the coin slide 67 is pushed in and the member 56 is pivoted (counterclockwise, from dotted to full line position, Fig. 5) the arm 62 of 35 the member 56 engages the lug 63 on the piston 64 of the dash pot 65 and thereby moves the latter (downwardly, from dotted to full line position, Fig. 5). In this manner the dash pot 64—65 times the operation or speed of the member 56 as well 40 as the lug 41 and the contact 42.

When the coin slide 67 is pushed in (right to left, Fig. 1) the inner end portion 80 of the same engages the upper end portion 81 of the member 82, thereby pivoting the latter, at 83 (counterclockwise, from full to dotted line position, Fig. 1), thus moving the angled portion 85 of the member 82 away from under the arm 86 of the gate 94, thus allowing the latter to fall, by gravity, (Fig. 1), whereupon the balls 21—22 which 45 are disposed on the ball seat 20 will roll by gravity down the inclined surface 95 of the ball seat 20 into the bucket or ball carrier 97, whereupon they may be elevated up to the opening 17 and dumped through the latter onto the runway 15 50 (Fig. 2), by operating the handle 100 and chain 99.

When the ball carrier 97 is lifted, by means of the handle 100 and chain 99, the arm 96 thereon (Fig. 1) engages the arm 111 of the gate 94 and 60 thereby lifts the latter, and at the same time raising the ball carrier 97 off from the arm 108 of the latch member 104, and as the gate 94 is thus raised the spring 87 pivots the latch member 104, at 107, in a clockwise direction, Fig. 1, 65 thus projecting the notched portion 106 of the latch member 104 under the arm 111 of the gate 94 and thereby latching the gate 94 in raised position until the ball elevator or carrier 97 is lowered into engagement with the arm 108 of the 70 latch member 104, whereupon the latter will be pivoted, at 107 (clockwise, Fig. 1) so as to move the notched portion 106 thereof out of the path of movement of the arm 111 of the gate 94, it being noted that as the gate 94 is lifted the spring 75 87 acts upon the latch member 82 to project the

angled extension 85 thereof under the arm 86 of the gate 94, thus latching the gate 94 in raised position. The gate 94 will remain thus latched in raised position until such time as the coin slide 67 is again operated (right to left, Fig. 1), 5 so as to pivot the latch member 82 (in a counterclockwise direction, from full to dotted line position, Fig. 1), thereby moving the angled portion 85 of the member 82 out from under the arm 86 of the gate 94, whereupon the latter will drop by gravity into lowered position so as to allow the balls to run off from the ball seat 20 into the ball elevator or carrier 97 (Fig. 2).

While I have illustrated and described the preferred form of construction for carrying my invention into effect, this is capable of variation and modification, without departing from the spirit of the invention. I, therefore, do not wish to be limited to the precise details of construction set forth, but desire to avail myself of such 15 variations and modifications as come within the scope of the appended claims.

Having thus described my invention, what I 20 claim as new and desire to protect by Letters Patent is:

1. In an amusement apparatus, a cabinet including a ball-playing surface provided with a ball seat and a plurality of balls of different diameter, a signalling instrumentality in the said cabinet, and means including a device actuated 30 by a ball disposed upon said ball seat for operating said signalling instrumentality, said means being effective to operate said signalling instrumentality only if and when a ball of predetermined diameter is the first disposed upon 35 said ball seat.

2. In an amusement apparatus, a cabinet including an inclined series of ball runways arranged one above the other in said cabinet and adapted to change the relative positions of a 40 group of balls traveling by gravity down the same, a ball seat arranged in the said cabinet below said runways and adapted to receive said balls from the lowermost of said runways, an indicating instrumentality in said cabinet, a 45 group of balls arranged in said cabinet and adapted to travel down said runways and one of said balls being larger in size or diameter than the others of said balls, and means, including a device actuated by the said balls when the latter 50 are disposed upon said ball seat in a predetermined manner, for operating said indicating instrumentality, said means being effective to operate said indicating instrumentality only if and when the said larger one of said balls is the 55 first of the same to enter into said ball seat from said ball runways.

3. In an amusement apparatus, a cabinet including a descending series of ball runways arranged one above the other in said cabinet and 60 adapted to change the relative positions of a group of balls traveling by gravity down the same, a ball seat arranged in the said cabinet below said runway and adapted to receive said balls from the lowermost of said runways, an indicating instrumentality in said cabinet, a group of balls arranged in said cabinet and adapted to travel down said runways and one of said balls having a diameter or size different from that of the others of said balls, and means, including a device actuated by the said balls, when the latter are disposed upon said ball seat in a predetermined manner, for operating said indicating instrumentality, said means being effective to operate 70 said indicating instrumentality only if and when 75 75 the latter are disposed upon said ball seat in a predetermined manner, for operating said indicating instrumentality, said means being effective to operate said indicating instrumentality only if and when 75

the said one of said balls is the first of the same to enter onto said ball seat from said ball runways and when the entire group of balls is disposed on said seat.

5 4. In an amusement apparatus, a cabinet including a ball-playing surface provided with a ball seat, an indicating instrumentality in the said cabinet, and an electric switch means actuated by a group of balls disposed upon said ball seat by a group of balls disposed upon said ball seat 10 for operating said indicating instrumentality, said switch means being effective to operate said indicating instrumentality only if and when the first one of said group of balls disposed upon said ball seat is a ball of a predetermined size or diameter different in size from the others of the group.

5. In an amusement apparatus, a cabinet including a vertically descending series of ball runways arranged one above the other in said cabinet and adapted to change the relative positions of a group of balls traveling by gravity down the same, a ball seat arranged in the said cabinet below said runway and adapted to receive said balls from the lowermost of said runways, an indicating instrumentality in said cabinet, a group 20 of balls arranged in said cabinet and adapted to travel down said runways and one of said balls having a diameter or size different from that of the others of said balls, and means, including an electric switch actuated by the said balls, when 25 the latter are disposed upon said ball seat in a certain manner, for operating said indicating instrumentality, said means being effective to operate said score-indicating instrumentality only if and when the said one of said balls is the first 30 of the same to enter onto said ball seat from said ball runways.

6. In an amusement apparatus, a cabinet including a ball playing surface provided with a ball seat, an indicating instrumentality in the 40 said cabinet, a plurality of balls in the said cabinet and adapted to be played upon the said ball-playing surface, one of the said balls having a diameter or size different from that of the others of said balls, and means for operating said indicating instrumentality and including a device actuated by the said balls when the latter are disposed upon said ball seat in a pre-determined manner in which the said one of said balls is disposed upon said ball seat in a predetermined position relative to the others of said balls.

50 7. In an amusement apparatus, a cabinet including a ball playing surface provided with a ball seat, an instrumentality in the said cabinet for operation by the playing of balls, a plurality of balls in the said cabinet and adapted to be played upon the said ball-playing surface, one of the said balls having a diameter or size different from that of the others of said balls, and means including a ball-operated electric switch effective to operate said instrumentality if and when the said one of said balls is disposed upon said ball seat in a predetermined position relative to the others of said balls.

65 8. In an amusement apparatus, a cabinet including a ball-playing surface provided with a ball seat and a number of balls of different size, an indicating instrumentality in the said cabinet, an electric switch for operating said instrumentality, means including a device controlled

only by a ball of predetermined size disposed upon said ball seat for operating said switch, and a member movably mounted in said cabinet above said ball seat and urged by said first-named means, into engagement with a said ball of predetermined size when the latter is the first disposed upon said ball seat, for controlling the effective operation of the said first-named means to operate said switch.

9. In an amusement apparatus, a cabinet including a descending series of ball runways arranged one above the other in said cabinet and adapted to change the relative positions of a group of balls traveling by gravity down the said runways, a ball seat arranged in the said cabinet below the said ball runways and adapted to receive balls from the lowermost of said runways, an indicating instrumentality in said cabinet, a group of balls in the said cabinet adapted to travel down the said ball runways and one of said balls having a diameter larger than the others of said balls, an electric switch for controlling said indicating instrumentality, means including a device actuated by the said balls when the latter are disposed in a certain manner upon said ball seat for operating said switch, said means being effective to operate the said switch only if and when the said larger one of said balls is the first of the same to enter onto said ball seat from said runways, and a member movably mounted in said cabinet 10 above the said ball seat and urged, by the said first-named means, into engagement with the said larger one of said balls, when the latter is disposed first upon said ball seat, for controlling the operation of said first-named means to operate said switch.

10. In an amusement device, a cabinet including a ball playing surface provided with a ball seat and a plurality of balls at least one of which is of larger diameter from the others, an indicating instrumentality in the cabinet, means for playing said balls onto said ball seat, control means for said instrumentality operable by the playing of said balls onto said ball seat in a predetermined manner, said means including a device in said ball seat operable by a ball thereon to actuate said instrumentality, and a member mounted for pivoting different distances by the first ball to enter the seat and being adapted depending upon the position of said larger diameter ball on said ball seat to render said first ball operated device ineffective to operate said instrumentality.

11. In an amusement device, a cabinet including a ball playing surface provided with a ball seat and a plurality of balls at least one of which is of larger diameter from the others, an indicating instrumentality in the cabinet, means for playing said balls onto said ball seat, and control means for said indicating instrumentality including switching means in said ball seat and operable by balls played thereon to actuate said indicating instrumentality, together with master switch means operable by said ball of larger diameter positioned in said ball seat in a predetermined manner to control the operation of said first switching means.
